[57] CLAIM

The ornamental design for a foldable spectacles, as shown and described.

DESCRIPTION

FIG. 1 is a front, left perspective view of a foldable spectacles in an extended position showing my new design; FIG. 2 is a front elevational view thereof;

FIG. 3 is a top plan view thereof;

FIG. 4 is a rear elevational plan view thereof;

FIG. 5 is a right side elevational view thereof, the left side elevational view being a mirror image thereof;

FIG. 6 is a bottom plan view thereof;

FIG. 7 is a perspective view of the foldable spectacles in an intermediate position between their extended position and their folded position in which intermediate position one of the arms of the spectacles is being turned and folded in front of the lens and the other of the arms is being folded behind the lens;

FIG. 8 is a first side view of the foldable spectacles in their folded position in which position the arms of the spectacles form a case for the lens part of the spectacles, the second side view being a mirror image;

FIG. 9 is a top view of the foldable spectacles in their folded position in which position the arms of the spectacles form a case for the lens part of the spectacles, the bottom view being a mirror image; and,

FIG. 10 is a first end view of the foldable spectacles in their folded position in which position the arms of the spectacles form a case for the lens part of the spectacles, the second end view being a mirror image.
